UNITED STATES PATENT OFFICE.

NEWELL B. PARSONS, OF CHICAGO, ILLINOIS, ASSIGNOR TO BELDEN MANUFACTURING COMPANY, OF CHICAGO, ILLINOIS, A CORPORATION OF ILLINOIS.

CAP OR HANDLE.

Application filed July 20, 1921. Serial No. 486,230.

To all whom it may concern:

Be it known that I, NEWELL B. PARSONS, a citizen of the United States, residing at Chicago, in the county of Cook and State of Illinois, have invented certain new and useful Improvements in Caps or Handles, of which the following is a specification.

My invention relates to improvements in caps or handles, and has special value in connection with caps or handles which require manipulation by hand and which are normally attached to parts subjected to a relatively high temperature.

The principal objects of my invention are to provide a cap or handle of the class described, so organized that the exterior may be composed of material of relatively less heat conductivity than metal and which will also present an ornamental appearance; to provide an article of the class described the exterior of which may be molded into any convenient and ornamental form; to provide an article of the class described which may be conveniently detached from the member or device to which the article is applied and which is fitted with a metal-to-metal connection whereby the article may be removed without impairing the fit or strength of the parts; to provide an article of the class described, so organized that, with the same mold for making the outer or ornamental portion of the article, many different styles and sizes of "inserts" or connecting means may be employed, thereby eliminating the necessity of providing a variety of styles and sizes of molds; to provide an arrangement whereby the moldable part may be made separately and the connector or insert subsequently secured thereto; and, in general, to provide an improved cap or handle of the character referred to.

In the drawings, which illustrate a specific embodiment of my invention and its application to filler caps for automobile radiators—

Fig. 1 is a plan view of the cap;
Fig. 2 is a section taken on the line 2—2 of Fig. 1;

Fig. 3 is an under-side plan view of said cap; and

Fig. 4 is a fragmentary section through the shell just after removing from the mold and prior to assembly of the cap-parts.

Referring to the drawings, it will be observed that I have shown a conventional

form of neck or pipe 10 which projects from the top of an automobile radiator, said pipe 10 in the present instance being externally threaded, as shown at 11. The cap in appearance is also of conventional outward design, having the usual series of flutes 12, by means of which the cap may be screwed or unscrewed from the threads 11 at the top of the pipe 10.

The outer shell or exterior portion 13 of said cap is constructed of bakelite or condensite, or similar material which, by means of heat and pressure, is capable of being transformed into a dense, heat-resistant, and permanently hard body. Said moldable material is relatively non-conducting; that is to say, its coefficient of heat conductivity is considerably less than that of the average metal, so that when the hand is applied to the shell 13 to detach the cap from the radiator, there will be no danger of burning or scalding the person. My invention, as will be seen later, effects a distinct cooling of the shell, whereby the cap is rendered still more convenient to adjust or handle without gloves.

An important feature of my invention consists in the assembling of the outer shell 13 and the connector portion or insert 14 of the complete cap, after the shell portion 13 has been removed from the mold, the inserts 14 being made separately. To this end I insert in the mold cavity a plurality (in the present instance three) of inclusions which take the form of metallic tubular rivets 15, the heads 16 of said rivets projecting well within the mold cavity during the molding operation, so that after the cap shell has been removed from the mold, the rivets 15 are found to be securely embedded in the shell material, the tubular shanks of the rivets projecting inwardly, as shown at 17 in Fig. 4. In practice, I prefer to make the shell 13 with a central recess and surrounded by a circumferential skirt or flange 18, said recess receiving the metallic insert 14 by which the cap is attached to the radiator snout 10. The diameter of said recess is preferably somewhat greater than the outer diameter of the insert 14, so that there will be some space between the insert and the inner surface of the outer shell. I believe this to be desirable in view of the difference in coefficient of expansion between the shell

material and the metal (usually brass) of which the insert 14 is constructed.

The insert 14 is made in the form of a flat thimble-like stamping, the lower or open end of which is externally threaded to fit the threads 11 on the radiator pipe 10. (If the radiator threads 11 are internal threads, the exterior of the insert 14 will naturally be threaded instead of having interior threads, 10 as in the present instance). A desirable feature of the specific embodiment herein shown is the making of the insert or thimble 14 with an expanded bottom or root, as shown at 19 which, besides facilitating the 15 tapping of the internal threads of the insert, constitutes a retainer for the annular gasket 20.

As will be seen by inspection of Fig. 2, the upper wall 21 of the brass insert is 20 perforated at three equispaced points in order to admit the shanks of the rivets 15, the edges of said perforations being curled upwardly, as shown at 22, in order to form facings which engage or abut against the 25 facing bosses 23 of the shell. It will be understood that after the shell portion of the insert 14 is placed in position in the shell recess with the shanks 17 of the rivets 30 extending through the apertures in the insert, and the tubular shanks, by means of a suitable spinning or upsetting tool, are formed into the shape shown in Fig. 2, thereby securely and rigidly uniting together the shell and the insert.

The particular cap herein shown is designed to permit the application of a thermometer of conventional form, as indicated in dotted lines at 24. To this end, I form 40 the shell portion 13 of the cap with a central hole for the purpose of receiving the nipple 25 formed as an integral part of the end wall of the insert. Said nipple 25 is threaded, as shown at 26, in order 45 to receive the threaded neck 27 of the thermometer, said thermometer having a shoulder or flange 28 adapted to be screwed tightly upon the faced-off upper end of said nipple 25, thus insuring the cap against 50 leakage.

The invention is of considerable value from a manufacturing standpoint, especially as applied to radiator caps of automobiles. This is in view of the many different threads, sizes, and styles of radiator snouts, necessitating a different insert or connecting means for practically every different make of automobile. With the method of construction heretofore generally practiced, in which the insert and the outer shell were assembled or united together as an incident to the molding of the outer shell, it was necessary to provide a different mold for each cap having a different style of insert, which meant that the

manufacturer of caps for replacement purposes had to carry in stock a set of molds for manufacturing caps for each make of automobile. Since my invention enables the 70 same outer shell to be used with many different styles of insert, it will be manifest that the large investment due to carrying in stock these various sets of molds is considerably reduced.

My improved article possesses several advantages over a similar article in which the insert is embedded or molded directly into the material of the shell. It will be observed that in my construction there is a space provided between the insert and the 80 outer shell 13, so that the heat which the insert receives directly from the heated snout 10 of the radiator, is not communicated directly to the shell material but must be transmitted across an air space. Hence, 85 my improved cap is decidedly cooler than a solid cap constructed according to the old practice.

A difference in the coefficient of expansion of the metal insert 14 and the material of the shell 13 has no deleterious effect with my construction, for the reason that, there being a free space between the insert and the outer shell, the insert may contract or expand independently of the shell and there 95 will be no tendency for the latter to split open, due to the greater expansion of the insert.

The term "metallic inclusion" is used to describe a metal part such as a rivet which 100 is imbedded in the molded material and secured thereto by such imbedding.

The herein described details of construction are merely illustrative of a single application of my invention, the scope of which should be determined by reference to the appended claims, said claims being construed as broadly as possible consistent with the state of the art.

I claim as my invention:

1. In combination, an outer shell of molded material formed with a circumferential flange or skirt, a metallic member molded into the body of said shell, and an inner shell attached to said outer shell by said member.

2. In combination, an outer shell of molded material formed with a circumferential flange or skirt, a metallic fastening member molded into the body of said shell and projecting from the inner face thereof, and an inner metallic shell connected to said member and contacting with said inner face.

3. In combination, an outer shell of molded material and formed with a circumferential flange or skirt, a facing abutment being formed on the interior surface of said shell, a metal part included in said face, a metallic thimble member loosely fitting within said shell enclosed by said flange and

having a portion engaging said face, and means uniting together said metal inclusion and said inner thimble.

4. In combination, an outer shell of molded material formed with a circumferential flange or skirt and provided with an inwardly projecting metallic pin having a head molded into said material, and an inner thimble member apertured to receive the projecting end of said pin, said pin being provided at its end with means whereby said thimble is secured in said outer shell.

5. In combination, an outer shell of permanently hard molded material provided with a plurality of inwardly pro-

jecting headed members included in said material, said members having projecting extensions, an inner thimble member apertured to receive said extensions and loosely fitting within said shell, and means on the ends of said extensions whereby said thimble is rigidly united to said outer shell.

6. In combination, an outer substantially cap-shaped shell of molded material provided with inwardly projecting metallic inclusions molded into its inner face, raised abutments formed at intervals upon said inner face, and an inner shell resting on said abutments and secured to said outer shell by said inclusions.

NEWELL B. PARSONS.
